UNITED STATES PATENT OFFICE.

JAMES JOLLY, OF BOLTON, ENGLAND, ASSIGNOR TO WHITIN MACHINE WORKS, OF WHITINSVILLE, MASSACHUSETTS, A CORPORATION OF MASSACHUSETTS.

COMBING MACHINE.

Application filed November 14, 1925. Serial No. 68,969.

The object of the invention is to simplify the construction and improve the action of Heilmann type combers for cotton or other fibres, and the invention is in the nature of an improvement on my prior Patent No. 1,516,101, and consists in the construction, relative arrangement and general organization of the parts of the combing head, as hereinafter described, and more particularly 10 pointed out in the appended claims.

Referring to the accompanying three sheets of drawings, Fig. 1 is a general cross section of one of the comber heads of a machine embodying my invention, showing 15 the assembled combing head mechanism in elevation and in the rear or combing position, certain parts being shown in section.

Fig. 2 is a top plan of the principal parts of Fig. 1, the lap feed chute and creel stand 20 being shown in section.

Fig. 3 is a section on III—III of Fig. 2 through the combing head with certain parts removed for clarity, and also shows the creel stand and its operating gears and the lap- 25 feed link-motion, in elevation.

Fig. 4 is a section on IV—IV of Fig. 2, showing only the bearing frame and the nipper frame.

Fig. 5 is a section on V—V of Fig. 2, with 30 the lap-feed mechanism removed, and

Fig. 6 is a section VI—VI of Fig. 5.

It will be understood that the illustrated structure constitutes but one of the combing heads of a cotton combing machine, which may have several heads all of identical structure and all driven by shafts extending lengthwise of the machine, and common to all of them. The frame 1 represents one of the intermediate frame uprights 35 which are located between adjacent heads and form the supports for the longitudinal shafts referred to as well as the other parts. The detail of the framing is not of consequence to the present invention, nor is this 40 invention concerned with the detaching and piecing mechanism, nor the drive-head mechanism which may be constructed according to the usual Heilmann or Nasmith design. The combing head mechanism comprises, in general, a main oscillating carriage or bearing frame, nipper mechanism carried thereby, a top comb and lap feed mechanism. The bearing frame is composed 45 of a cross bed 2 and two side legs 3 which are journalled below the nippers and preferably 50

on or concentrically with the comb cylinder shaft 4, so as to be capable of moving the nippers concentrically to the path of the comb needles. This frame is integrally formed with three pairs of upright posts, of 60 which the pair marked 5, are the connection lugs by means of which the frame is connected to the rock arms 6 of the longitudinal rock shaft 7. This shaft will be understood to be common to all the heads in the machine and to be appropriately driven by cam or otherwise, in the drive mechanism at the end of the machine. The lugs or posts 5 are each connected to one of the rock arms 6 by a two-part link, one part of which, 65 marked 8, is an L-shaped member jointed to the lug 5 and receiving the forward threaded end of the other part 9, in a perforation in its offset portion, 10 so that the link, as a whole, is adjustable as to its effective length; this is for the purpose of varying the angular relation between the bearing frame and the actuating rock shaft, and the method of adjustment will be obvious. The off-set end 10 of the link 8 serves as 70 75 the connection for the nipper frame spring 11, later referred to.

The two posts of the bearing frame 2—3 which are marked 12, constitute the support and bearings for the nipper frame and lap-feed mechanism, and the two posts, marked 13, are the supports for the arms 14 of the top comb 15. These top comb arms are hinged to said posts so that the top comb may be lifted and swung back as customary, 80 and each arm is provided with a lateral ear 16 (Fig. 2) carrying a set screw 17, which is adapted to rest on the heads of the front journal cap bolts of the posts 12 and thereby support the top comb, adjustably, 85 90 in its normal or working position. The top comb is thus carried by the oscillating bearing frame 2—3, but its position with reference to the axis of oscillation is constant, that is to say, it is not lowered into the tuft 95 as customary; such comb movement is not necessary in the present case because the tuft is raised into the top comb as later explained. The detail of the top comb and its several adjustments will be understood from 100 105 the drawings.

The nipper frame comprises a base or bed part 18 and two upstanding cheek plates 19 provided with gudgeons by which it is journalled in the posts 12 of the bearing 110

frame; it is also provided with upstanding posts 20, connected at their upper ends, to the nipper frame springs 11 above referred to. The tension of these springs tends to rock the nipper frame to the position indicated in Fig. 3, wherein its rear set screws 21 rest against the upper surface of the cross bed 2 of the bearing frame. The nipper frame carries two forwardly located set screws 22, one at each end, the function of which is to engage the top surfaces of the side legs 3 of the bearing frame to limit the extent to which it may rock in the opposite direction. The cross plate 18 of the nipper frame carries the usual cushion plate, and it will be understood that the adjustment of the set screws 22 determines the distance of the cushion plate from the path of the combing needles on the comb cylinder 23, while the rear set screws 21 determine its position when detaching.

The nipper-knife 24 is carried, adjustably, on two nipper-knife levers 25, each of which is fulcrumed on one of the posts 5 of the bearing frame, and preferably by the same pin which connects the actuating link 8 to said post. It will be seen in Fig. 2 that the front and rear arms of the nipper knife levers 25 are off-set; the relation of the lever to its fulcrum post 5 is also shown in Fig. 6. The two rear arms of the levers are thus brought closer together and are connected by a cross rod 26 carrying a cam bowl 27, which is wiped by a cam 28, adjustably carried on the rock shaft 7 when the latter swings forwardly to about the position indicated in Fig. 5, thus opening the nipper jaws, as they swing forward to the detaching rolls. The adjustment of the cam 28 on the rock shaft determines the time of such opening. When not engaged with the nipper cam 28, the nipper knife is held closed on the cushion plate by the two upper springs 29, which depress the nipper frame and cushion plate until the forward set screws 22 find their predetermined bearing on the bearing frame 3. The nipper springs are connected to the crossrod 26 between the rear arms of the nipper levers and to brackets 29^a fixed on a rod supported in the creel stand. When the nipper knife has been opened by the operation of the nipper cam 28, as just described, the nipper frame springs 11 rock the nipper frame until the rearward set screws 21 engage the cross member 2 of the bearing frame, as above described. Thus one set of springs operates to oscillate the nipper frame in one direction and another set in the opposite direction. It may be noted here that the two jaws of the nipper mechanism, that is, the cushion plate and the nipper knife, are not coaxially pivoted as customary; the cushion plate, being secured on the bed 18 of the nipper frame, oscillates about the axis of

the gudgeon bearings 12 on the frame 2-3, whereas the nipper knife oscillates about the axis of the fulcrum pin in the lug 5 on the frame 2-3, which axis is in rear of the gudgeon axis. This helps in directing the tuft into the comb cylinder needles and is one of the features of this invention. It will be observed further that the use of a moving member, such as the cam 28, as the means for controlling the nippers eliminates the back bar and other appurtenant frame parts which have heretofore been common in swinging nipper frame combers and thus simplifies the apparatus.

The lap feed roller 30 is removably supported and pressed down upon the top of the cushion plate by a pair of lap feed roll levers 31, which are adjustably fulcrumed at 32 in slots in the nipper frame posts 20. The feed roll thus swings with the nipper frame. The rear ends of the levers 31 are connected to the feed roll springs 33 and the upper ends of the latter are connected to the nipper frame posts 20 on the opposite side from the nipper frame springs 11. The end of the feed roller 30, right-hand in Fig. 2, is provided with the usual ratchet box, containing a ratchet wheel and pawl and provided with a lever 34, which is detachably connected to a feed link 35, shown more clearly in Fig. 3. It has heretofore been customary to actuate the ratchet box, such as 34, by means of a link, such as the link 35, which is attached at its rear end to a fixed part of the machine framing, so that as the feed roll advances to the detaching rolls, the lever 34 is held and thereby rotates the feed roll to feed the lap forwardly. According to the present invention, the feed link 35 moves in phase with the oscillating nipper mechanism and in the same direction but at a lesser or different rate of movement, so that the amount of rotation thereby imparted to the feed roll is the differential of such movements. For this purpose, the rear end of the feed link 35 is pivoted, adjustably, to an arm 36 on a lay rock shaft 37 journalled in the creel stand and provided, at one end of the machine, with a crank arm 38, by which it is rocked. This latter arm is adjustably connected to, and rocked by, a link connection 39 with the pawl arm 40 of the creel-feed bell-crank 40-41. This bell crank is driven from the main rock shaft 7 by a link 42 connecting its arm 41 with the creel drive arm 43 on said shaft. The oscillation of the bell-crank 40-41, imparted through the pawl and ratchet wheel 40^a to the creel gears 44, intermittently rotates the creel rollers 45 so as to unwind the lap from the supply roll resting thereon. The organization of this creel-feed is well known and will be clear enough from the drawing, and it may be substituted by other forms of feed, according to preference. The

rocking movement of the creel feed bell crank 40—41 rocks the lay rock shaft 37 so as to advance the lap feed link 35 at the same time as the nippers and feed roll are advanced by the rock shaft arms 6, but the rate or extent to which the link is advanced depends upon its own position on the arm 36 and upon the position of the link rod 39 on the crank arm 38. These 10 positions can be changed to give any desired differential movement of the feed roll, as will be evident, and in practice the feed link 35 of each combing head is permanently set on its arm 36 and adjustment of the lap feed of all the heads is then made simultaneously in all heads by changing the position of the link 39 on the crank arm 38. This adjustment is easily and quickly made and the adjustment of the creel feed can be 20 easily accommodated to it by varying the position of link 42 on the bell crank.

The lap feed apron 46 is made in two sections hinged at 47, in order to accommodate the movement of the combing head mechanism relative to the creel stand; it is supported at its upper end on the creel rock shaft 37 and at its lower end on a small cross rod 48 (Fig. 3), carried by the lap feed roll levers 31. The apron is removable from 30 these supports.

The operation of the creel and combing head mechanism, meaning thereby the top comb, nippers and feed roll, is produced entirely by the main rock shaft 7. When this 35 shaft draws the bearing frame 2—3 to the rearward position of Fig. 1, which is the cylinder-combing position, the nipper cam has parted from the cam bowl 27 and the nipper knife springs 29 then hold the nipper knife 24 closed against the tuft on the cushion plate and the nipper frame depressed to its lowest position. When the needle half-lap has passed from the tuft, the rock shaft 40 swings the bearing frame toward the detaching and piecing rolls, and co-incidentally, the lap feed roll revolves to feed the lap and almost immediately thereafter the nipper 45 cam 28 engages the bowl 27 and thereby relieves the spring pressure of the springs 29, on the nipper knife. This allows the nipper frame to swing the combed tuft to its elevated position as the effect of the springs 11, and immediately thereafter the 50 nipper knife opens as indicated in Fig. 5. In this position, the tuft is entered into the bite of the detaching rolls and then drawn off through the teeth of the top comb in the familiar manner; on the return movement of the parts the action is of course reversed 55 except that the lap feed roll remains stationary and the pawl rides over the ratchet teeth.

The following is claimed:

1. In a comber, the combination of an oscillating bearing frame, means for oscillating said frame, a nipper frame pivoted on

said bearing frame, a top comb carried on said frame and normally supported in fixed relation thereto, and nipper knife levers adapted to rock the nipper frame with relation to said bearing frame. 70

2. In a comber, the combination of an oscillating bearing frame, an oscillating nipper frame pivotally mounted therein, a nipper knife lever pivoted on the bearing frame and adapted to oscillate said nipper frame, a shaft for oscillating said bearing frame and means on said shaft for operating said nipper knife lever. 75

3. In a comber, an oscillating bearing frame, and a nipper frame carrying the cushion plate and lap feed means and pivotally mounted in the bearing frame, in combination with a nipper knife fulcrumed on the bearing frame on an axis eccentric to the pivotal axis of the nipper frame. 80 85

4. In a comber, the combination of an oscillating bearing frame, an oscillating nipper frame and cushion plate pivotally mounted therein, a nipper knife fulcrumed on the bearing frame and adapted to oscillate said nipper frame, a top comb pivoted on the bearing frame and normally held in fixed relation thereto, and a shaft for oscillating said bearing frame and nipper knife. 90

5. In a comber, the combination of an oscillating bearing frame, an oscillating nipper frame pivotally mounted therein, a nipper knife and top comb separately pivoted on the bearing frame, a rock shaft for oscillating said bearing frame and means on said shaft for operating said nipper knife. 95 100

6. In a comber, the combination of an oscillating frame, a nipper knife and nipper levers carried thereby, and a moving member engaged by said levers on the forward swing of said frame for operating said nipper knife. 105

7. In a comber, an oscillating combing head structure including a nipper knife lever, a shaft to oscillate said structure and a cam carried by said shaft for operating said lever. 110

8. In a comber, an oscillating combing head mechanism including a nipper knife lever, a rock shaft to oscillate said mechanism, a cam carried by said rock shaft for operating said lever, and means to adjust said cam to vary the time of operation thereof. 115

9. In a comber, the combination of a comb shaft, a bearing frame mounted to oscillate about the axis thereof, means for oscillating the bearing frame, a nipper frame movably carried on said bearing frame, lap feed mechanism carried on said nipper frame and means driven in phase with said bearing frame but at a different rate for actuating said lap feed mechanism. 120 125

10. In a comber, the combination of oscillating combing head mechanism including 130

- a lap feed roll, an intermittent creel feed, and means whereby said creel feed operates said lap feed roll.
11. In a multi-head comber, the combination of oscillating bearing frames carrying nippers and lap-feed rolls, of means for simultaneously adjusting the extent of rotation of said feed rolls.
12. In a comber, an oscillating comber head structure including lap feed mechanism, a shaft for oscillating said structure and a lay shaft controlling the rotation of said feed mechanism.
13. In a multi-head comber, oscillating combing mechanism including lap-feed rolls, a rock shaft connected to said rolls for operating the same and means for varying the rotation of said rock shaft independently of said oscillating mechanism.
14. In a comber, the combination of oscillating combing mechanism including a lap feed roll, a creel roller, means for oscillating said mechanism and intermittently advancing said roller, and an operating connection between said means and said lap feed roll.
15. In a comber, the combination of oscillating combing head mechanism including a lap feed roll, an actuating rock shaft therefor, a creel roller, connections whereby said roller is operated by said rock shaft and means whereby said connections control the operation of said lap feed roll.
16. In a comber, an oscillating comber head mechanism including a ratchet-driven lap feed roll, an intermittent creel feed including a rock shaft, and means for adjustably connecting said creel rock shaft to the ratchet arm of said lap feed roll.
17. In a comber, an oscillating comber head mechanism including a ratchet-driven lap feed roll, a main rock shaft to oscillate said mechanism, a creel feed having a rock shaft operated by said main rock shaft, and a connecting rod between said creel rock shaft and the ratchet arm of said lap feed roll.
18. In a comber, a main rock shaft, operating connections therefrom to an oscillating comber head mechanism which includes a lap feed roll and to the creel feed, and means whereby the creel feed controls the rotation of said lap feed roll.
19. In a comber of the kind described, the combination with the comb shaft, a bearing frame mounted to oscillate about the axis thereof, and means for oscillating said frame, of a top comb, nipper frame and nipper knife each pivoted on said bearing frame and a lap feed roll carried on the nipper frame.
20. In a comber of the kind described, the combination with an oscillating bearing frame, of a nipper frame and nipper knife lever separately and directly pivoted thereto, an actuating shaft, and means whereby said shaft oscillates said bearing frame and independently operates said nipper knife lever.
21. In a comber of the kind described, the combination with the comb shaft, an oscillating bearing frame, of a nipper frame and nipper knife levers carried by said bearing frame and a shaft for oscillating said bearing frame and directly operating said lever.
22. In a comber, an oscillating frame carrying lap-feed means, nipper knife lever and top comb, and a rock shaft provided with means for oscillating said frame and directly operating said nipper knife lever.
23. In a comber, a nipper frame oscillating toward and from the detaching rolls, a nipper knife coating with said frame, nipper knife levers supporting said knife, said levers being closer together at the rear of the frame than at their point of connections to the nipper knife, a cross rod connecting the rear ends of said levers and means in rear of said nipper frame for actuating said nipper knife levers.

In testimony whereof, I have signed this specification.

JAMES JOLLY.
